Inventor

Samuel Marcus

By his Attorney

L. George Tanoff

UNITED STATES PATENT OFFICE

SAMUEL MARCUS, OF RIVERDALE, NEW YORK, ASSIGNOR TO MARKON MANUFACTURING CO., INC., OF NEW YORK, N. Y., A CORPORATION OF NEW YORK

TONGUE AND TEETH FOR DOLLS' HEADS

Original application filed October 21, 1926, Serial No. 143,031. Patent No. 1,689,925, dated October 30, 1928. Divided and this application filed August 28, 1928. Serial No. 302,550.

This invention relates to dolls and like toys, and particularly to the tongue and teeth for such articles, the present application being in the nature of a division of pending application Serial No. 143,031, filed October 21st, 1926, now Patent No. 1,689,925, issued October 30th, 1928.

An object of the present improvement is to provide a tongue and teeth set which may be readily handled and attached in position within a doll head.

A further object is to so construct the set that it may be very cheaply and easily manufactured, while yet being entirely practical and appropriate for its purpose.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:—

Fig. 1 is a front elevational view of a tongue and teeth set constructed in accordance with this invention, and

Fig. 2 is a vertical sectional view through the structure shown in Fig. 1 and showing the same as applied in position within a doll head, the portions of the doll head being illustrated by dotted lines.

Referring to the drawings for describing in detail the structure illustrated therein, the reference character I indicates the front portion of a doll head, the mouth opening being shown at 1.

The tongue and teeth set in the present instance is made up from a single piece of appropriate material, such as sheet celluloid, sheet metal, or the like, stamped, pressed or otherwise formed to provide the necessary characteristics, namely a tongue portion G and a teeth portion H.

These portions are formed by pressure exerted against the inner or concealed surface

of a base or body portion 2, being thus caused to project from the forward or exposed surface of said body.

The base or body portion 2 may be of any appropriate extent, being in the present instance made to project in all directions radially from the tongue G so that it may serve as a background for the tongue. The tongue and the body portion 2 may both be made of a reddish color, the portion 2 thus representing the interior of the mouth.

An extension 3 may be provided projecting in one direction, as for instance upwardly, intended to lie substantially flat against the inner surface of the portion of the doll head immediately above the mouth opening and to be held fixed to the doll head by an appropriate cement or other medium as 4.

While the cement 4 may if desired be extended to rigidly connect the body portion 2 with the inner surface of the doll head at other points about the mouth opening, it preferably is placed to fix rigidly only the extension 3, thus leaving the remainder of the body portion, including the tongue, only resiliently held in position so that if the tongue be pressed by a child's finger during play the tongue may yield backwardly and thus add an element of interest for the amusement of the child.

It will be understood of course that such yielding movement of the tongue will be permitted by the natural springiness of the material, such as celluloid or spring metal, from which the device is made.

The teeth H are shown as being formed from the same piece of material as the other parts, consisting merely of forwardly punched or pressed portions of the body portion 2 at a proper location just above the tongue G. In forming these teeth they may if desired have their side and bottom edges 5 and 6 severed from the body, the upper portions of the teeth being left however integral with the body as at 7. In this way the teeth are allowed to project straight downwardly in an appropriate position while the base or body 2 from which they are punched may be pressed backwardly as by pressure from a child's finger.

The relatively narrow portions as 8 and 9 at opposite sides of the teeth provide an area of weakness constituting a hinge connection between the portion of the device which is intended to be fixed by the cement 4 and the tongue, thus permitting easy backward flexing of the tongue at all times.

Since in some instances it may be desirable to so form the teeth that all of the edge portions thereof will remain in integral connection with the body, that is as indicated by the connecting portions 10 in Fig. 2, it is to be understood that the present invention is not intended to be limited to severing certain of the edges as above suggested.

The portion of the piece of material representing the teeth will of course be made of a whitish color. The piece of material employed may be colored red and white in predetermined localities before the material is pressed or shaped to provide the tongue and teeth, or the different parts may be colored after the material has been formed-up. Or on the other hand if desired a piece of material may be employed having one of the necessary colors throughout its surface extent, and the other color be applied thereto after the forming operation, as for instance a piece of red sheet celluloid may be utilized as the material from which the device is made, and then after this is properly shaped the teeth portion may be coated with a white paint or enamel to cover the red surface of this part.

As many changes could be made in this construction without departing from the scope of the invention as defined in the following claims, it is intended that all matter contained in the above description, or shown in the accompanying drawings, shall be interpreted as illustrative only and not in a limiting sense.

Having thus described my invention, what I claim as new and desire to secure by Letters Patent is:—

1. A tongue and teeth structure for doll heads, said structure comprising a single piece of sheet material bent forwardly at one point to provide the representation of a human tongue projecting from its forward surface, and bent forwardly at another point to provide the representation of human teeth projecting from said forward surface in appropriate relation to the tongue.

2. A tongue and teeth structure for doll heads, said structure being formed from a single piece of material shaped in different localities to provide the representation of a human tongue and human teeth respectively, and said piece of material having a portion serving as attaching means by which to connect the structure in position within the doll head.

3. A tongue and teeth structure for doll heads, said structure being formed from a

single piece of sheet material pressed to provide the representation of a human tongue projecting at one side thereof and the representation of human teeth projecting from the same side thereof spaced from the tongue.

4. A tongue and teeth structure for doll heads, said structure being formed from a single piece of sheet material pressed to provide the representation of a human tongue projecting at one side thereof and the representation of human teeth projecting from the same side thereof spaced from the tongue, and said piece of material having a portion by which it may be connected with the doll head.

5. A tongue and teeth structure for doll heads, said structure being formed from a single piece of sheet material pressed to provide the representation of a human tongue projecting at one side thereof and the representation of human teeth projecting from the same side thereof spaced from the tongue, and said piece of material having a portion relatively nearer to the teeth than to the tongue serving as attaching means by which to connect it in position within the doll head.

6. A tongue and teeth structure for doll heads, said structure being formed from a single piece of sheet material pressed to provide a tongue projecting at one side thereof and teeth projecting from the same side thereof spaced from the tongue, and said piece of material having a portion adjacent the teeth serving as attaching means by which to connect it in position within the doll head, together with means whereby the portion of the piece of material between the attaching means and the tongue is rendered flexible to facilitate movement of the tongue upon application of pressure thereto.

7. A tongue and teeth structure for doll heads, said structure being formed from a single piece of sheet material shaped at one point to provide a tongue projecting therefrom, said piece of material being also shaped to provide teeth at a locality above the tongue, and said piece of material having an extension projecting upwardly beyond the teeth constituting attaching means by which to connect the structure in position within the doll head.

8. A tongue and teeth structure for doll heads, said structure being formed from a single piece of sheet material shaped at one point to provide a tongue projecting therefrom, said piece of material having a flexible portion extending away from the tongue constituting means by which the tongue may be flexibly supported upon the doll head, and said piece of material having teeth pressed therefrom as an integral part thereof in appropriate relation to the tongue.

9. A tongue and teeth structure for doll heads, said structure being formed from a

single piece of sheet material shaped at one point to provide the representation of a human tongue projecting therefrom, and said piece of material being shaped also to provide the representation of human teeth in appropriate relation to the tongue and within the margin of said piece of material, the portion of the material constituting the teeth being severed from the remainder of the material throughout a portion of its extent but remaining in integral connection with the material throughout the remainder of its extent.

10. A tongue and teeth set for doll heads, said set comprising a base part having the representation of a human tongue projecting therefrom, a teeth portion comprised in the base spaced from the tongue, attaching means also comprised in the base, and all of said parts being formed from a single piece of sheet material.

11. A tongue and teeth set for dolls and the like comprising a sheet of material of reddish color upon a part of one of its surfaces, and of whitish color on another part of said surface, said sheet of material being formed to provide the representation of a tongue in that portion which is of reddish color and to provide the representation of teeth in that portion which is of whitish color.

12. A tongue and teeth set for dolls and the like comprising a base portion pressed outwardly from one surface to provide a tongue extension at the exposed opposite surface, said base portion being also pressed outwardly to provide a teeth portion at said exposed surface adjacent the tongue portion, the tongue portion being of reddish color on its exposed surface and the teeth portion being of whitish color on its exposed surface.

In testimony whereof I affix my signature.

SAMUEL MARCUS.
